(57) CLAIM

I Claim, the ornamental electrical connector keying arrangement, as shown and described.

DESCRIPTION

FIG. 1 is a perspective view of a first embodiment of my electrical connector keying arrangement in accordance with the invention;

FIG. 2 is an end view of the embodiment of my electrical connector keying arrangement illustrated in FIG. 1;

FIG. 3 is a left-side elevation view of the first embodiment of my electrical connector keying arrangement illustrated in FIG. 1;

FIG. 4 is a plan view of the first embodiment of my electrical connector keying arrangement illustrated in FIG. 1;

FIG. 5 is a perspective view of a second embodiment of my electrical connector keying arrangement in accordance with the invention;

FIG. 6 is an end view of the second embodiment of my electrical connector keying arrangement illustrated in FIG. 5;

FIG. 7 is a left-side elevation view of the second embodiment of my electrical connector keying arrangement illustrated in FIG. 5; and,

FIG. 8 is a plan view of the second embodiment of my electrical connector keying arrangement illustrated in FIG. 5.
